UNITED STATES PATENT OFFICE.

ISAAC STROUSE, OF NEW HAVEN, CONNECTICUT, ASSIGNOR TO LEWIS SCHIELE & CO., OF NEW YORK, N. Y.

DESIGN FOR A CORSET.

SPECIFICATION forming part of Design No. 13,288, dated September 5, 1882.

Application filed August 10, 1882. Term of patent 7 years.

To all whom it may concern:

Be it known that I, ISAAC STROUSE, of New Haven, in the county of New Haven and State of Connecticut, have invented a new Design for Corsets; and I do hereby declare the following, when taken in connection with accompanying drawing and the letters of reference marked thereon, to be a full, clear, and exact description of the same, and which said drawing constitutes part of this specification, and represents a side view.

This invention relates to a design for the ornamental staying of the hip-section of a corset; and it consists in series of stays arranged relatively to each other, as shown in the accompanying illustration.

The hip-section consists of three portions, upper, middle, and lower, with a transverse band dividing each from the next. A, the upper section, represents stays as running diagonally from front to rear. B, the middle section, represents two series of stays, the one running from the center diagonally to the rear, the

other from the center diagonally to the front. The lower section, C, represents stays as running diagonally from the top to the front. The respective sections are separated by transverse bands D and E, each representing a series of horizontal stays, all as shown in the accompanying illustration.

30

I claim—

The design for corset a herein described, consisting of the upper portion, A, representing diagonal stays, the bottom portion, C, also representing diagonal stays, the intermediate section, B, representing stays running respectively from the center to the rear and front, the transverse bands D E between the said sections, each representing a series of horizontal stays, as shown in the accompanying illustration.
